Attorney.

UNITED STATES PATENT OFFICE.

WILLIAM D. BREMER, OF CEDAR FALLS, IOWA.

ABRADER FOR DISK-HARROW BLADES.

1,172,763.

Specification of Letters Patent. Patented Feb. 22, 1916.

Application filed August 26, 1915. Serial No. 47,479.

To all whom it may concern:

Be it known that I, WILLIAM D. BREMER, a citizen of the United States of America, and a resident of Cedar Falls, Blackhawk 5 county, Iowa, have invented certain new and useful Improvements in Abraders for Disk-Harrow Blades, of which the following is a specification.

My invention relates to improvements in 10 abraders for disk-harrow blades, and the object of my improvement is to furnish for such blades grinding-means movably and adjustably mounted adjacent to the blades, and adapted for convenient use in sharpening 15 the blades at any time. This object I have accomplished by the means which are hereinafter described and claimed, and which are illustrated in the accompanying drawings, in which:

Figure 1 is a plan view of a disk-harrow equipped with my improved abraders. Fig. 2 is a detail side elevation of one of the 20 rotary blades, showing one of my abrading devices mounted in operative position relative thereto. Fig. 3 is a detail view, enlarged, of the rocker-arm and abrader. Fig. 4 is a side elevation of the parts shown in said Fig. 3. Fig. 5 is a detail side elevation, showing a modified form of abrader 25 and means for actuating it, mounted in grinding position against a rotary blade.

Similar numerals of reference denote corresponding parts throughout the several views.

The concavo-convex blades 16 are fixed 30 on a rock-shaft 17, the latter mounted in bearings carried by arms 29 and 30, the latter adjustably secured to the harrow-frame 27, with other braces 28 connecting 35 said bearings and frame. An angle-bar 2 is fixed on arms whose lower ends are supported on said shaft, said angle-bar adapted to be adjustably connected to the frame 27 by means not shown.

Each blade 16 is supplied with an abrading-device adapted to be shifted into or out 40 of grinding contact with the convex face of an adjacent blade 16 at and near its edge. This abrader consists of a block 14 of abrasive such as carborundum, removably held 45 between two clamping-arms 12, adjustably mounted on the threaded arm 11, and held by the nuts 13. These clamps may be adjusted along the arm 11 to permit the 50 abrader to be used on blades of different diameters. Each arm 11 is fixed on a rock-

body 3, which latter has depending ends 15, orificed to be mounted to rock upon the shaft 1, and retained in place by collars 9 on the shaft, provided with set-screws 10. Sleeves 8 are seated upon the shaft 1, and have projecting plates 4 with slots 5, whereby they may be adjustably mounted 60 on the angle-bar 2 by means of bolts 6 and nuts 7.

An arm 18 is fixedly mounted on the rock-shaft 1, and a rod 19 is connected between its upper end and a hand-lever 20 pivoted on a cross-bar 25 of the frame 27. A detent 24, controlled by a spring 23, is connected to 70 a rod 22, actuated by a finger-piece 21 pivoted on said lever, and is adapted to engage either of two grooves 27 on a sector-rack 26 fixed on the cross-bar 25, whereby the abrader 14 may be brought into or out 75 of grinding contact with the blade 16, when said arm 11 is rocked appropriately. By the said means, the blade may be re-sharpened at any time, when the harrow is in use.

Fig. 5 shows a modified form of the device. A rotatable abrader 39 is mounted between forks of a rock-arm 36, the latter hinged at 35 to the angle-bar 2. The continued shaft of said abrader carries a sheave 40. A sheave 31 is fixed on the shaft 17, 80 and a pair of idlers 33 are fixed on a common shaft rotatable in a bearing on said angle-bar 2. A belt or cable 32 connects the sheave 31 with one of said idlers, while another belt or cable 38 connects the other idler 85 with the sheave 40. A rod 37 pivotally connected to the arm 36 serves to shift the abrader 39 into or out of grinding contact with the blade 16. The rotating shaft 17 of 90 said blade thus rotates the abrader 39. Instead of sheaves and cables shown, sprocket-wheels and chains may be employed.

Other modifications of my device may be employed without departing from the scope or principle of my invention.

Having described my invention, what I claim as new, and desire to secure by Letters Patent, is:

1. A disk-sharpening attachment for cultivators and the like, comprising a rock-shaft, an arm fixed thereon, clamping-means on the end of said arm, a sharpening device held removably by said clamping-means, another arm fixed on said rock-shaft, a lever, and a linking-connection between said lever 105 and the second-mentioned arm.

2. A disk-sharpening attachment for cul-

tivators and the like, comprising a rock-shaft, an arm fixed thereon, clamping-means adjustable longitudinally on said arm, a sharpening device held releasably by said 5 clamping-means, and means for rocking said shaft to bring said sharpening device into or out of contact with a disk.

3. A disk-sharpening attachment for cultivators and the like, comprising a fixed 10 transverse bar, a rock-shaft adjustably mounted on said bar, an arm adjustably mounted on said rock-shaft, clamping-means

adjustably mounted on said arm, sharpening-means releasably held by said clamping-means, and means for rocking said shaft to bring said sharpening device into or out 15 of contact with a disk.

Signed at Cedar Falls, Iowa, this 7th day of August, 1915.

WILLIAM D. BREMER.
